UNITED STATES PATENT OFFICE

FRED ALDEN AND LOUIS M. COONEY, OF SAGINAW, MICHIGAN

SANITARY MILK CONTAINER

Application filed November 12, 1928. Serial No. 318,718.

The present invention relates to improvements in paper receptacles and has reference more particularly to a container for milk or cream.

5 One of the important objects of the present invention is to provide a milk container that is formed of destructible material so that after the container or receptacle has been emptied of its contents, the same can be 10 thrown away, thus promoting sanitation.

A further object is to provide a sanitary milk container that will be strong and durable yet very inexpensive in its manufacture, the container comprising a frame structure 15 formed from compressed paper, a covering for the frame of transparent material being arranged thereunder in such a manner as to prevent leakage of the liquid from the container yet enabling the contents to be visible 20 at all times.

Other objects and advantages of the invention will become apparent from the following description when taken in connection with the accompanying drawing.

25 In the accompanying drawing wherein like reference characters indicate corresponding parts throughout the several views:

Figure 1 is a side elevation of our improved sanitary milk container, parts being shown 30 in section, and

Figure 2 is a detail perspective view of the frame.

In the drawing, wherein for the purpose of illustration is shown the preferred embodiment of our invention, the numeral 1 designates generally the frame that is formed from compressed paper, and the frame is formed in different sizes, such as for example, 35 gills, half pints, pints, and quarts. The frame includes a cylindrical cup shaped bottom 2, and extending upwardly from the upper edge thereof at equidistantly spaced points are the ribs 3, said ribs gradually converging from their intermediate portions to 40 ward their upper ends and terminating in outwardly curved fingers 4, over which is fitted the ring like member 5 also formed of compressed paper, the upper edge portion of this ring like member being directed inward- 45 ly over the upper free ends of the fingers 4,

thence being disposed downwardly and terminating in the annular flange 6 for receiving the usual bottle stopper disc, not shown, the shoulder 7 providing a mean for retaining the stopper disc against casual displacement 55 from the ledge or flange 6.

The sanitary receptacle or container further includes the provision of a transparent covering 8 that is disposed within the frame in the manner as clearly shown in the 60 drawing. This transparent covering is preferably formed of paper, and so shaped as to adhere to the shape of the frame and the lower edge portion of the covering 8 extends below the upper edge of the cup shaped bottom 2, while the upper edge of the transparent covering terminates at a point adjacent the shoulder 7 so as not to interfere with the filling of the container or with the discharge of the contents thereof when the 70 cap or disc is removed.

It is of course understood that the lower edge portion of the transparent covering is attached to the cup shaped bottom in such a manner as to prevent leakage of the liquid 75 from the container. If desired, the transparent covering may be arranged on the outside of the frame.

The provision of a container of the above mentioned character will obviate the use of 80 glass milk bottles, thus reducing the cost in the operation of a dairy, as these destructible containers can be manufactured at a very low cost.

Furthermore, the container is adapted to be 85 destroyed after the contents have been discharged therefrom, thus promoting sanitation.

A sanitary container of the above mentioned character will be attractive and the 90 same will be at all times positive and efficient in carrying out the purposes for which it is designed. If desired, reinforcing ribs may be arranged on the bottom face of the cap shaped member 2 for strengthening the structure. 95

While we have shown the preferred embodiment of our invention it is to be understood that minor changes in the size, shape and arrangement of parts may be resorted 100 to without departing from the spirit of the

invention and the scope of the appended claims.

Having thus described the invention, what we claim as new and desire to secure by Letters Patent is:—

- 6 1. A milk receptacle constructed of de-
structible material, said receptacle including
a frame, that comprises a bottom cup-shaped
member, strips extending upwardly from the
10 cup-shaped bottom, a ring-like member fitted
over the upper ends of the strips, the upper
edge of the ring-like member being disposed
inwardly and so bent as to form a bottle cap
receiving latch, and a covering for the frame.
- 15 2. A milk receptacle constructed of de-
structible material, said receptacle including
a frame, that comprises a bottom cup-shaped
member, strips extending upwardly from the
10 cup-shaped bottom, a ring-like member fitted
over the upper ends of the strips, the upper
edge of the ring-like member being disposed
inwardly and so bent as to form a bottle cap
receiving latch, a covering of transparent
25 material disposed around the strips, the up-
per edge of the covering terminating at the
top of the ring-like member, the lower edge
of the covering terminating adjacent the bot-
tom of the cup-shaped member.
- 30 3. A milk receptacle constructed of de-
structible material, said receptacle comprising
a circular cup-shaped bottom formed of
compressed paper, strips of the same material
extending upwardly from the upper edge of
35 the cup-shaped bottom at spaced intervals,
the upper end portions of the strips being
disposed in converging relation, and termi-
nating in outwardly curved fingers, a com-
pressed paper ring shaped to fit over the out-
40 wardly curved fingers, the upper edge por-
tion of the ring being disposed inwardly and
thence downwardly and terminating in a bot-
tle cap supporting flange, and a transparent
covering inside the frame and arranged in a
leak-proof manner.
- 45 In testimony whereof we affix our signa-
tures.

FRED ALDEN.
LOUIS M. COONEY.
